(74) *Attorney, Agent, or Firm* — Design IP
DESCRIPTION

FIG. 1 is a front view of a first image of a first embodiment of an portion of a display screen with animated graphical user interface showing my new design;

FIG. 2 is a front view of a second image thereof;

FIG. 3 is a front view of a third image thereof;

FIG. 4 is a front view of a fourth image thereof;

FIG. 5 is a front view of a first image of a second embodiment of an portion of a display screen with animated graphical user interface showing my new design;

FIG. 6 is a front view of a second image thereof;

FIG. 7 is a front view of a third image thereof;

FIG. 8 is a front view of a fourth image thereof;

FIG. 9 is a front view of a first image of a third embodiment of an portion of a display screen with animated graphical user interface showing my new design;

FIG. 10 is a front view of a second image thereof;

FIG. 11 is a front view of a third image thereof;

FIG. 12 is a front view of a fourth image thereof;

FIG. 13 is a front view of a first image of a fourth embodiment of an portion of a display screen with animated graphical user interface showing my new design;

FIG. 14 is a front view of a second image thereof;

FIG. 15 is a front view of a third image thereof; and,

FIG. 16 is a front view of a fourth image thereof.

In the first embodiment, the appearance of the transitional image sequentially transitions between the images shown in FIGS. 1 through 4. In the second embodiment, the appearance of the transitional image sequentially transitions between the images shown in FIGS. 5 through 8. In the third embodiment, the appearance of the transitional image sequentially transitions between the images shown in FIGS. 9 through 12. In the fourth embodiment, the appearance of the transitional image sequentially transitions between the images shown in FIGS. 13 through 16. The process or period in which one image transitions to another image forms no part of the claimed design.

The broken line showing of a portion of a display screen in FIGS. 1 through 16 forms no part of the claimed design. The broken line showing of text and portions of the graphical user interface in FIGS. 1 through 16 represents environmental subject matter and forms no part of the claimed design. The greyscale fill shown within the icons in FIGS. 9 through 12 illustrates a contrast in appearance.
